UNITED STATES PATENT OFFICE

WILLIAM C. WATKINS, JR., OF BRIDGETON, NEW JERSEY

DESIGN FOR A GLOBE FOR LIGHTING FIXTURES

Application filed March 10, 1933. Serial No. 47,431. Term of patent 14 years.

To all whom it may concern:

Be it known that I, WILLIAM C. WATKINS, JR., a citizen of the United States, residing at Bridgeton, in the county of Cumberland and State of New Jersey, have invented a new, original, and ornamental Design for a Globe for Lighting Fixtures, of which the following is a specification, reference being had to the accompanying drawing, forming part thereof and showing my new design.

Figure 1 is a rear elevation,
Figure 2 is a side elevation, and
Figure 3 is a front elevation.

I claim:

The ornamental design for a globe for lighting fixtures, as shown.

WILLIAM C. WATKINS, JR.
